(57) **CLAIM**

The ornamental design for a trimless downlight, as shown and described.

DESCRIPTION

FIG. 1 is a perspective view of a trimless downlight showing embodiment 1 of my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a partial enlarged rear view taken from FIG. 3;

FIG. 9 is a perspective view of a trimless downlight showing embodiment 2 of my new design;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof;

FIG. 16 is a partial enlarged rear view taken from FIG. 11.

The broken lines shown in the FIGS. 3, 8, 11 and 16 are

included for the purpose of showing the portion for the

enlarged views and form no part of the claimed design.
